UNITED STATES PATENT OFFICE.

JOHN VOLESKE, OF PORTLAND, OREGON.

POWER-CUTTER.

1,204,090.

Specification of Letters Patent.

Patented Nov. 7, 1916.

Application filed February 25, 1915. Serial No. 10,517.

To all whom it may concern:

Be it known that I, JOHN VOLESKE, a citizen of the United States, residing in the city of Portland, county of Multnomah, and 5 State of Oregon, have invented certain new and useful Improvements in Power-Cutters, of which the following is a specification.

My invention relates to power cutters, 10 and more particularly to a portable device especially adapted for cutting wire cable, iron bars and the like by hand, and has among its salient objects,—to provide a portable cutter, of the character referred to, 15 which can be carried by one man from place to place, and which can be folded into a comparatively small bundle for convenience in carrying it; to provide in a device of the character referred to mechanism which can 20 be operated by one man and which requires very little manual strength in order to operate it; and, in general, to provide a simple, practical and comparatively cheap power cutter of the character referred to. 25 In order that others may understand my invention I have shown in the accompanying sheet of drawings one practical embodiment thereof, which I will now describe.

Figure 1 is a side elevation of my cutter, 30 set up ready for use; and Fig. 2 is a top plan view thereof, with the handle cut off at its pivot.

Referring now more in detail to the drawings, my invention comprises a lower cutter member 1, provided with a cutter jaw 1', and at its rearward end with a pivotally attached base supporting piece 2, an upper cutter member 3, having a cutting jaw 3', adapted to coöperate with the jaw 1' of 35 the cutter member 1, said cutter members being pivotally secured together, as at 4, close to the cutting jaws thereof, as indicated. The upper cutter member is provided with a spool, or drum, 5, and with a pin, 40 6, to receive an operating cable 7, which is attached at one end to said pin 6, then passed under a pulley 8, on the lower cutter member 1, and thence up to the drum, 5, upon which it is to be wound, as said drum is turned. Said drum, 5, is operated by a ratchet 9, which is turned by means of the handle, 10, having a pawl, 11, adapted to engage said ratchet, as said handle is operated in a manner which is well understood. 45 A holding pawl, 12, is provided to

hold said ratchet as it is turned by operating the handle 10. The handle 10 is pivoted on the same axle, or shaft, 5', with the ratchet 9, and the drum 5, and can be turned down along side the jaw member 3, and 60 said jaw member 3, is moved down close to the jaw member 1, in folding said members together, in a manner which will be clear from the construction shown.

In operation the base member 2 is turned 65 crosswise of the jaw member 1, as shown, and the upper jaw member is raised sufficiently to allow a cable C to be inserted between the jaws 1' and 3' in the manner indicated. The handle is now operated back 70 and forth to turn the ratchet 9, and the drum 5, thereby drawing the jaw members 3 and 1 together, and cutting the cable, in a manner which will be clearly understood.

I am aware that changes can be made in 75 the invention as here illustrated without departing from the spirit thereof, and I do not, therefore, limit the invention to the particular form here shown, except as I may be limited by the hereto appended claims. 80

I claim:

1. A power cutter of the character described, comprising a lower cutter member having a cutting jaw and a supporting base piece, an upper cutter member pivotally connected thereto and having a cutter jaw to coöperate with the jaw of the first member, a cable connection between the cutter members for drawing them together, a ratchet-operated winding member on one of said 90 cutter members adapted to wind said cable, and means for operating said ratchet-operated winding member.

2. A power tool of the character referred to, comprising two members pivoted together intermediate their ends scissor fashion, and provided with cutting jaws at one end, one of said members being provided with a pulley, or sheave, and the other of said members being provided with a cable drum, an operating cable connecting said members around said sheave, or pulley, and said cable drum, and a ratchet and hand lever mechanism for operating said cable drum, whereby to wind up said cable and 100 draw said members together.

3. A power cutter of the character described comprising in combination, a cutter member having a cutting jaw, a supporting base and a pulley, a second cutter member 110

having a cutting jaw and a ratchet-operated drum, and pivotally connected to said first cutter member, a cable attached to said second cutter member and passed around the 5 pulley on said first cutter member, and to said drum, and a handle pivotally connected to said second cutter member and adapted to operate said drum, to wind up said

cable and draw said cutter members together, substantially as described.

Signed at Portland, Multnomah county, Oregon, this 19th day of February, 1915.

JOHN VOLESKE.

In presence of—

I. M. GRIFFIN,
R. B. FRENCH.
